UNITED STATES PATENT OFFICE.

JOHN B. WATLING, OF CHICAGO, ILLINOIS.

VENDING MACHINE.

Application filed July 7, 1923. Serial No. 650,048.

My invention relates more particularly to target vending machines having a mechanism operated by coins which are projected at the targets, for dispensing ball gum and like articles.

The principal objects of my invention are to provide an improved coin controlled vending mechanism; to afford a simple and reliable device for vending ball gum and the like; to insure agitation of the articles in the magazine and prevent pocketing or cramping of the articles so that they will not fail to feed; to provide for operation of the mechanism and delivery of the articles purchased at the front end of the machine where the gun or projector is located; to feed all the coins whether they hit the targets or not, to the vending machine mechanism so that each coin serves to operate or permit operation of the vending mechanism; to display the coins which miss the targets in such a manner that they are readily observed by the operator so that he can distinguish the shots which have missed the targets; and in general to afford a simple and dependable vending machine in a form which will attract the interest of people and cause them to make purchases.

On the drawings:

Fig. 1 is a perspective view of a vending machine embodying my improvements with parts broken away to disclose details of construction;

Fig. 2 a view looking at the rear of the machine with the back wall removed;

Fig. 3 a fragmentary view on the line 3—3 of Fig. 2;

Fig. 4 a top view of the machine with the upper portions broken away to disclose the operating mechanism;

Fig. 5 a top view of the coin controlling mechanism; and

Fig. 6 a fragmentary top view of the bottom wall of the magazine.

Referring to the drawings, the reference numeral 1 indicates a suitable cabinet or case which is preferably of elongated form with a housing 2 at the upper end. A partition 3 separates the cabinet 1 from the housing 2 and is provided with a number of openings 4 which serve as targets at which coins are projected by means of a gun 5. This gun 5 is loosely secured in the front wall 6 of the cabinet so that it may be readily moved about for taking the proper aim at the target open-

ings 4, and has a coin slot 7 to admit a coin of the proper denomination, which upon operating the trigger 8, is projected from the inner end of the gun into the interior of the casing 1. The mechanism of the gun 7 for shooting the coin at the target openings 4 is not shown, as devices of this character are already well-known and the particular mechanism forms no part of my present invention.

A window 9 is arranged directly above the gun 5 so that the operator may view the targets in the cabinet and take the proper aim. The top 10 of the cabinet 1 is preferably transparent so that the interior of the cabinet is visible and also may be illuminated by exterior lighting.

A casing 11 is secured to the rear side of the wall 3 to receive the coins which pass through the target openings 4 and direct same down into a cup shaped member 12 which tapers to an opening at the bottom, which is closed by the slide 13. This slide holds each coin deposited in the cup shaped member 12 in position to permit operation of the vending mechanism, and upon such operation the slide 13 is moved laterally to permit the coin to drop down into a coin box 14.

This machine is designed to vend ball gum, which is contained in a magazine 15, formed between the rear wall 16 of the housing 2 and the partition 3, and having the bottom formed by a plate 17 which has the opposite end portions slightly inclined to an intermediate outlet opening 18. The casing 11 for directing the coins from the target openings to the coin controlled mechanism is preferably cut away as shown to provide a large opening 65 at the center with portions of the casing at each side forming coin chutes, said opening being in communication with the magazine 15 so that the articles in the magazine fill in the opening 65. Said opening extends down to the bottom wall 17 of the magazine and the partition 3 which forms the front wall of the magazine, is provided near the lower end of the opening 65 with a window opening 66 closed by a heavy glass 67 so that the operator can see the character of articles dispensed by the machine and the proprietor of the machine can ascertain, without opening up the magazine, when the magazine is empty or nearly empty.

A frame 19 is secured to the side walls of

the machine below the magazine bottom plate 17, and has a tube 20 extending upwardly therefrom to the opening 18 in the plate 17 so as to discharge the balls of gum 5 successively from the magazine onto a plate 21. This plate 21 is supported by a bracket 22, depending from the frame 19, at a suitable distance below the frame 19 to accommodate the balls of gum between the plate 10 21 and frame 19, and projects over the edge of a chute 23 which leads forwardly and downwardly through an opening in the front wall 24 of the casing 1, said wall being provided exteriorly with a cup 25 to 15 retain the balls so that they may be conveniently obtained by the operator.

The cup member 12 is secured at its upper end to the frame 19 and at its lower end has a forwardly extending arm 26 to which the 20 forward end of the slide 13 is pivoted as indicated at 27, and this slide is held up against the bottom of the cup by a cross strap 28 which is secured to lateral extensions at the bottom of the cup 12. Lugs 29 25 depend from such lateral extensions to hold the cross strap 28 properly spaced from the bottom of the cup member to accommodate the slide 13, and these lugs serve as stops to limit the movement of the slide and other 30 mechanism connected therewith.

The rear end of this slide 13 beyond the guide 28 is bent upwardly as indicated at 30 and has a portion extending rearwardly from the upper end, said portion comprising 35 a loop 31 which is normally positioned so as to register with the lower end of the tube 20 to surround the lowermost ball 32 which rests on the plate 21, and this loop serves when the slide 13 is moved laterally to the 40 right, viewing same in Fig. 3, for releasing the coin in the bottom of the cup 12, to simultaneously move the lowermost ball 32 over beyond the end of the plate 21 so that it drops down into the chute 23. A plate portion 33 extends laterally from the loop 31 adjacent the lower surface of the frame 19 so as to serve as a gate to close the lower 45 end of the tube 20 when the loop 31 is moved over to deposit a ball of gum into the 50 chute 23.

For operating the slide 13 there is a rod 34 running lengthwise of the machine and projecting through a bearing 35 in the front wall, a handle 36 being provided on the exposed forward end of the rod for turning same. The rear end of this rod is journaled in a hanger 37 depending from the frame 19, and there is a crank arm 38 fixed on the rod 34 near the rear end and connected by a link 39 to a pivot pin 40 which depends from the slide 13. A spring 41 has one end connected to the pin 40 and the other end connected to a hook 42 on the side wall of the machine so as to normally hold the slide 13 in the 65 position shown in Fig. 2 wherein it closes

the bottom of the cup member 12 and holds the loop 31 in register with the lower end of the tube 20.

The mechanism just described is arranged to be normally locked against operation to 70 a sufficient extent to move the ball 32 over into the chute 23 when there is no coin in the cup member 12. To this end a coin detector 43 is pivoted at 44 on the extension or arm 26 and has a finger 45 at the outer end working 75 in a notch 46 in the side wall of the cup 12 adjacent the lower end and immediately above the slide 13. A spring 47 connects the coin detector 43 with a lateral projection 48 at the lower end of the cup member 12 and exerts a tension to project the finger 45 80 through the slot 46 into the interior of the cup member 12. An arm 49 extends laterally from the slide 13 and has a notch 50 in the forward edge cooperating with a depending finger 51 of the coin detector 43 so that when there is no coin in the cup member 12, movement of the slide 13 in a direction to feed the ball 32 into the chute 23 brings the notch 50 into engagement with the depending finger 51 of the coin detector, the spring 47 acting at such time to throw the outer end of the coin detector 43 rearwardly to cause the depending finger 51 to engage and interlock with the notch 50. The forward edge 85 portion of the arm 49 at the side of the notch next to the slide 13 is arranged to deflect the finger 51 forwardly as the slide 13 returns under the tension of the spring 41 to the normal position and thereby withdraw the finger 45 from the cup 12 and hold it in the withdrawn position.

When a coin has been deposited in the cup member 12, it drops down to the bottom of the cup and rests flat upon the upper surface of the slide 13 in the position to obstruct inward movement of the finger 45. Therefore, when the handle 36 is operated in the direction shown by the arrow in Fig. 1, with a coin resting in the bottom of the cup member 12, the coin detector 43 is held from movement to engage the notch 50, and the slide 13 is then capable of sufficient movement to slide the ball 32 of gum over beyond the end of the plate 21 and also to uncover the lower end of the cup member 12 105 and permit the coin to drop down into the coin box 14. The portion of the cup member at the lower end may be so arranged that the coin will fall even though the finger 45 110 is bearing against the edge of the coin, or the arm 49 beyond the notch 50 may be suitably formed to engage the depending finger 51 sufficiently after the notch 50 has passed thereby to release the pressure of the finger 45 on the edge of the coin.

In machines for vending ball gum or articles of a similar nature, it sometimes occurs the articles in the magazine become packed in such a manner that they interlock and 130

prevent feeding thereof to the vending mechanism. To avoid this objection and provide means which will insure repeated agitation of the contents of the magazine, I have provided an agitator 52 which comprises an arm pivoted to the frame 19 at 53 and having a head 54 at the outer end embracing the tube 20. This head is adapted to be projected through the opening 18, which latter is suitably enlarged for this purpose and the head is cut away at one side as indicated at 55 so that the balls may roll onto the upper end of the tube 20 at that side when the head 54 is elevated. For operating this agitator the arm thereof is provided near the pivoted end with a plate 56 depending through an opening 57 in the frame 19 and provided with an annular slot 58 which is engaged by the pin 59 on the outer end of the crank arm 60, which crank arm is fixed on the shaft or rod 34. A certain amount of movement of the rod 34 and parts connected therewith occurs before the notch 50 engages the finger 51 when there is no coin in the cup member 12, and this movement is sufficient to throw the head 54 upwardly to an extent sufficient to agitate the contents of the magazine. When there is a coin in the cup member 12 and the mechanism is therefore capable of its full movement the head 54 is projected upwardly a greater distance and agitates the contents of the magazine more thoroughly than when there is no coin in the cup member 12. However, with this construction any movement of the handle 36 serves to agitate the contents of the magazine and this serves to insure sufficient agitation of the contents of the magazine so that the articles are at all times loosely conditioned and free to enter the outlet tube 20.

In machines of this type which have been heretofore constructed, the coins which did not pass through the target openings dropped down into the bottom of the casing 1 and the operator was then unable to secure an article from the magazine 15. In my machine a pan 61 is provided in the case 1 with oppositely inclined sides which are pitched from front to rear of the machine and lead into the centrally disposed gutter 62 which leads to the cup member 12. The latter is formed in its front wall with an opening 63 with which the rear end of the gutter 62 registers, said end of gutter and adjoining portions of the inclined walls being supported by a flange 64 on the member 12, which flange conforms to the end portion of the pan 61. Thus the machine operates to dispense an article regardless of whether the coin passes through the target openings 4 or not, as those which miss the openings 4 drop down onto the pan 61 and are conveyed thereby to the cup member 12. This arrangement, which is very simple and

inexpensive, makes this machine appeal to the public more than machines in which the vending machine is not operable except when a coin passes through the target opening 4. Moreover, this arrangement makes it readily apparent whether the operator has hit the target openings or not, as the coins which fail to pass through the openings 4 drop down into the pan 61 in plain view of the operator, whereas, in previous machines they drop down into the bottom of the compartment and the operator frequently is not able to tell whether he had hit the target opening or not.

While I have shown and described my invention in a preferred form, I am aware that various changes and modifications may be made without departing from the principles of my invention, the scope of which is to be determined by the appended claims.

I claim as my invention:

1. In a vending machine, the combination of a case having a wall at one end provided with a target aperture, a coin projector at the other end of the case for projecting coins at the target aperture, a magazine behind the wall at the end of the casing and having a mechanism controlled by the coins which pass through said aperture for dispensing articles from the magazine, and means for collecting the coins from the projector which fail to pass through said aperture and conveying same through the wall to said mechanism.

2. In a vending machine, the combination of a case having a wall at one end provided with a target aperture, a gun loosely secured at the other end of the case and adapted to receive and project coins at the aperture, a magazine behind the wall at the end of the casing and provided with a release mechanism operable by the coins to permit removal of an article from the magazine, means also at the rear of the aforesaid wall for conveying the coins from the aperture to the release mechanism, and a pan extending forwardly from said wall below said aperture and adapted to convey the coins deposited thereon to the aforesaid release mechanism.

3. In a vending machine, the combination of an elongated case provided with a housing at the rear end, a partition separating the case and housing and provided with a plurality of target openings, a gun loosely secured at the front of the case and adapted to receive and project coins at the target openings, a pan extending from front to rear of the case and having oppositely inclined side portions leading into an intermediate gutter which is inclined downwardly and rearwardly to an aperture in the aforesaid partition, a magazine at the rear end of the casing back of the partition, a coin controlled release mechanism for per-

mitting removal of articles from the magazine, and means for conveying coins from the aperture at the rear end of the gutter and from the target openings to the coin release mechanism.

4. In a vending machine, the combination of a casing divided longitudinally by a transverse partition into two compartments, a target in the partition, a coin projector in one of the compartments and mounted on the front wall of the casing, a magazine in the other compartment, coin controlled release mechanism in said latter compartment for permitting removal of articles from the magazine, and means in the first mentioned compartment and extending from end to end thereof for receiving coins which fail to strike the target and conveying them to the aforesaid release mechanism in the latter compartment.

5. In a vending machine, the combination of a casing, a coin projector extending into the casing, a magazine provided with release mechanism operated by coins from the projector, a vertical partition in the casing separating the projector from the magazine and release mechanism and said partition provided with apertures constituting targets for the coins, means behind the partition for conveying coins from the target apertures to the release mechanism, and means in front of the partition for conveying coins which fail to pass the apertures to the said release mechanism.

35 6. In a vending machine, the combination of a casing, a coin projector extending into the casing at one end thereof, a magazine provided with release mechanism operated by coins from the projector and located at 40 the other end of the casing, a partition in the casing forming two compartments, one for the coin projector and the other for the magazine and release mechanism, and said partition provided with apertures constituting targets for the coins, means behind the partition and in the magazine and release mechanism compartment for conveying coins from the target apertures to the release mechanism, and means in front of the partition and in the coin projector compartment 50 and extending from end to end thereof for conveying coins which fail to pass the target apertures to the release mechanism.

7. In a vending machine, the combination of a casing divided longitudinally by a transverse vertical partition into two compartments, a coin projector in the front compartment, magazine and release mechanism operated by coins from the projector carried in the rear compartment, said partition being provided with apertures constituting targets through which coins are adapted to pass from the projector to the release mechanism, and means extending the 65 full length of the coin projector compart-

ment and inclining toward and to the partition for delivering coins which fail to pass through the apertures to the release mechanism.

8. In a vending machine, the combination 70 of a projector for discharging coins, a target, a receptacle for receiving the coins striking the target, a retainer for receiving the coins from the receptacle, a trough for receiving the coins not striking the target, 75 said trough leading to the retainer, a magazine for articles to be dispensed, and coin controlled mechanism associated with the retainer and with the magazine for discharging a single article from the magazine for 80 each coin deposited in the retainer.

9. The combination in a vending machine, a magazine, a passage from the magazine for articles to be dispensed, a plate beneath the passage, a coin receiving receptacle 85 provided with a coin discharge opening, a control device formed with a body having a slide portion, a loop and an intermediate plate portion between the loop and slide, said member being movable to one position to dispose the slide portion to close the coin discharge opening and to dispose the loop portion over the plate in position to receive and retain an article thereon; and to another position to open the coin discharge passage 90 and to dispose the intermediate plate portion to close the passage from the magazine and the loop to release the article retained thereby, and means for actuating said control 95 device.

10. The combination in a vending machine, a magazine, a passage from the magazine for articles to be dispensed, a plate beneath the passage, a coin receiving receptacle provided with a coin discharge opening, a control device formed with a body having a slide portion, a loop and an intermediate plate portion between the loop and the slide, said member being movable to one position to dispose the slide portion to close the coin discharge opening and to dispose the loop portion above the plate to a position to receive and retain an article thereon; and to another position to open the coin discharge opening and to dispose the intermediate plate portion to close the passage from the magazine and the loop portion to release the article retained thereby, locking means connected with the control device for limiting the movement of the same when there is no 110 coin in the receptacle, and means for actuating said control device.

11. The combination in a vending machine, a magazine, a passage from the magazine for articles to be dispensed, a plate beneath the passage, a coin receiving receptacle provided with a coin discharge opening, a control device comprising a movable body formed to receive and retain articles 115 on the plate and close the opening in said 120 125 130

coin receiving receptacle, means for moving said body to uncover the opening in said coin receptacle and move and release an article from the plate, a portion of said body adapted to close the passage from the magazine in said latter position, and means for locking the body in its first position when there is no coin in the receptacle.

12. In a vending machine, the combination of a casing divided longitudinally by a partition into two compartments, a target in the partition, a coin projector mounted on the front wall of the casing to project into the front compartment, a magazine in one of the compartments, coin-controlled release mechanism for receiving coins and permitting removal of the articles from the magazine, and means in the first mentioned compartment and extending from end to end thereof for receiving coins which fail to strike the target and conveying them to the aforesaid release mechanism.

13. In a vending machine, the combination of a casing divided longitudinally and vertically throughout its height by a partition into two compartments, a target aperture in the partition, a coin projector mounted on the front wall of the casing to project into the adjacent compartment, a magazine in one of the compartments in a plane below the projector, coin-controlled release mechanism in one of the compartments for permitting removal of the articles from the magazine, means for feeding the coins from the projector to the release mechanism, means in the first mentioned compartment and extending from end to end thereof for receiving coins which fail to strike the target and pass into the aperture thereof and conveying them to the aforesaid release mechanism, and means actuated from the front of the casing for operating the release

mechanism to discharge an article to be vended into a suitable cup exteriorly of the casing.

14. In a vending machine, the combination of a casing divided longitudinally near one end by a partition into two compartments, a target in the partition, a coin projector mounted on the front wall of the casing, a single magazine in one of the compartments, a single coin-controlled release mechanism in one of the compartments for permitting removal of articles from the magazine, a coin chute leading from the target, means in the first mentioned compartment and extending from end to end thereof for receiving coins which fail to strike the target and conveying them to the aforesaid release mechanism, and manually operated means at the front of the casing for operating the release mechanism to discharge an article.

15. In a vending machine, a casing, a transverse partition dividing the casing into two compartments, a target on the partition having an aperture, a coin projector mounted on the front wall of the casing, a magazine for articles to be vended, coin-controlled release mechanism in one of the compartments, a coin delivery chute leading from the target aperture, means in the first mentioned compartment and extending from end to end thereof for receiving coins which fail to strike the target and conveying them to the release mechanism, and means at the front of the casing and extending beneath the last mentioned means for operative connection with the coin-controlled release mechanism to actuate the latter for releasing an article to be delivered exteriorly of the casing.

JOHN B. WATLING.
